[57] CLAIM

The ornamental design for a rocking ramp for bicycle
riders, or similar article, as shown and described.

DESCRIPTION

FIG. 1 is a top plan view of a rocking ramp for bicycle
riders, or similar article, showing our new design.

FIG. 2 is a side elevation view thereof, the opposite side
being a mirror image of that shown;

FIG. 3 is a bottom plan view thereof.

FIG. 4 is an end elevation view thereof, the opposite
end being a mirror image of that shown.

FIG. 1.

FIG. 2.

FIG. 3.

FIG. 4.
